D. O. ROYSTER,
BEVERAGE COOLING AND DISPENSING APPARATUS.
APPLICATION FILED DEC. 10, 1918.

1,377,630.

Patented May 10, 1921.

Inventor
David O. Royster
By *J.W. Gurnee, Atty.*

UNITED STATES PATENT OFFICE.

DAVID O. ROYSTER, OF ST. LOUIS, MISSOURI.

BEVERAGE COOLING AND DISPENSING APPARATUS.

1,377,630.

Specification of Letters Patent. Patented May 10, 1921.

Application filed December 10, 1918. Serial No. 266,035.

To all whom it may concern:

Be it known that I, DAVID O. ROYSTER, a citizen of the United States, residing at city of St. Louis, State of Missouri, have invented a certain new and useful Improvement in Beverage Cooling and Dispensing Apparatus, of which the following is a full, clear, and exact description, such as will enable others skilled in the art to which it appertains to make and use the same, reference being had to the accompanying drawings, forming part of this specification.

My invention relates to improvements in an apparatus for the cooling and dispensing of beverages or potable liquids, and particularly the so-called cereal beverages now generally manufactured and sold throughout the country.

The particular object of my invention is to provide a relatively simple and efficient cooling and dispensing apparatus which, when properly constructed, presents a neat and finished appearance and which apparatus can be economically used for handling beverages or the like which are put up in relatively large containers by the manufacturers and in such containers delivered to the retailers.

My invention contemplates the use of a jacket or the like in the form of a keg or barrel and said jacket being surmounted by a removable member which comprises a housing and a pan, the latter being arranged below the dispensing faucets or outlet valves and adapted to receive the cups or containers into which the beverage is drawn.

A further object of my invention is to provide a dispensing apparatus wherein the various parts entering into its construction may be readily assembled and taken apart and which provision is particularly desirable when it becomes necessary to cleanse or repair the various parts of the apparatus.

With the foregoing and other objects in view, my invention consists in certain novel features of construction and arrangement of parts hereinafter more fully described, claimed and illustrated in the accompanying drawings in which—

Figure 1 is a perspective view of a dispensing apparatus of my improved construction.

Fig. 2 is a plan view of the upper portion of the apparatus and with a part of the cover broken away.

Fig. 3 is an enlarged vertical section taken approximately upon line 3—3 of Fig. 2.

Referring by numerals to the accompanying drawings which illustrate a practical embodiment of my invention 10 designates 60 a receptacle or jacket preferably in the form of a barrel or keg.

Positioned within this jacket and secured thereto in any suitable manner is a vertically disposed wall 11 of wire netting or 65 perforated sheet metal, and the space 12 between said wall and the wall of the jacket is adapted to be filled with ice for the purpose of cooling the beverage dispensed from the apparatus.

Removably positioned on top of jacket 10 is a ring 13, the front portion of which carries a relatively short or low vertically disposed wall 14 and the rear portion carrying a higher wall 15. These wall members are 75 preferably constructed of wood or suitable material and both inner and outer faces are sheathed with suitable sheet metal as designated by 16.

The front edges of the higher wall 15 are 80 united by a transversely disposed wall 17; both faces of which are sheathed with sheet metal as designated by 18.

Connected to the lower portions of the walls 15 and 17 and the corresponding portion of ring 13 is a bottom wall or plate 19, the top surface of which is sheathed and said sheathing and bottom are perforated as designated by 20 to provide drain openings. Thus the walls 15, 17, and 19 provide a boxlike structure of semi-circular 85 contour, and removably positioned on top of said structure is a cover 21, of wood or analogous material and having both surfaces sheathed with sheet metal.

The front wall 14 is approximately half the height of wall 15 and removably positioned with the lower portion of said wall 14 and in front of the lower portion of wall 17 is a semi-circular member 22 of wood 100 or the like, the top surface of which is sheathed with metal and said member being perforated to form drain openings 23.

Fitted to the top of member 22 is a handle 24 which enables said member 22 to be 105 readily lifted from its normal or closed position.

Positioned in the upper portion of front wall 17 is a pair of faucets 25 and 26 of any desired construction and removably po- 110

- sitioned within the wall 11 in jacket 10 is a beverage container 27 preferably of the type disclosed in my copending application, filed December 10, 1918, Serial No. 266,033.
- 5 The upper end of this container is provided with a neck upon which is removably positioned a cap 28 of the type described in my copending application just mentioned, and leading from this cap 28 upwardly through the bottom plate 19 and through the chamber within the semi-circular housing to faucet 25 is a beverage discharge pipe 29.
- 10 Located in the bottom of the chamber within the housing composed of the walls 15 and 17 is a coil 30 through which water is adapted to circulate and be cooled and one end of this coil is detachably connected to the faucet or outlet valve 26. The other 15 end of this coil extends downwardly through bottom 19 and is connected to a water supply pipe 31, the latter projecting outwardly through the upper portion of jacket 10.
- 15 Located on the exterior of jacket 10 is an air pump 32 of ordinary form and leading therefrom through the wall of the jacket to the cap 28 is a compressed air pipe 33. A waste pipe 34 leads from the lower portion of jacket 10 and is for the 20 purpose of carrying off water resulting from the melting of the ice placed in said jacket.
- 20 Located on the exterior of jacket 10 is an air pump 32 of ordinary form and leading therefrom through the wall of the jacket to the cap 28 is a compressed air pipe 33. A waste pipe 34 leads from the lower portion of jacket 10 and is for the 25 purpose of carrying off water resulting from the melting of the ice placed in said jacket.
- 25 It will be understood that the containers 27 are delivered from the manufacturers to the retailers or owners of the dispensing apparatus, and when one of these containers is delivered the cap 28 is positioned thereupon.
- 30 To place the container in proper position within the jacket and make the proper connections, said container is placed within the wall 11 and the space 12 between said wall and the wall of the jacket is filled with ice.
- 35 The upper part of the apparatus is now placed on top of the jacket and by removing member 22 access may be had to the upper portion of the jacket for the purpose of connecting the lower end of pipe 29 and the inner end of pipe 33 to the cap 28.
- 40 Member 22 is now returned to its proper 45 position, after which pump 32 is operated to force air under pressure through pipe 33 to the interior of the container 27 and by virtue of such pressure the liquid within the
- 55 container will be forced upwardly through pipe 29 whenever valve 25 is opened.
- 60 The space within the housing composed of the walls 15 and 17 can be filled with ice thereby cooling the water within coil 30 and likewise cooling that portion of the beverage that occupies the upper portion 65 of pipe 29; consequently the last portion of the contents of container 27 will be cooled when drawn from the faucet 25 and delivered to a customer. The water resulting from the melting of the ice in this compartment passes downwardly through the jacket through drain openings 20 and any waste or overflow from faucets 25 and 26 will pass downwardly into the jacket 70 through drain openings 23.
- 75 A dispensing apparatus of my improved construction is comparatively simple, can be easily and cheaply manufactured, can be readily assembled or taken apart, and provides efficient and economical means for cooling and dispensing beverages and the like.
- 80 It will be readily understood that minor changes in the size, form, and construction of various parts of my dispensing apparatus can be made and substituted for those herein shown and described without departing from the spirit of my invention, the scope of which is set forth in the appended claim.
- 85 I claim:
- 90 In a beverage cooling and dispensing apparatus, the combination with a receptacle, and a beverage container removably positioned therein, of a member removably positioned on top of the receptacle and serving as a cover therefor, said member comprising a housing and a pan, said pan being provided with a removable bottom, the bottoms of the housing and the pan being pro- 95 vided with drain openings, a faucet seated in the wall of the housing above the pan, a tubular connection from the beverage container to said faucet, a portion of which tubular connection passes through the 100 housing.
- 105 In testimony whereof I hereunto affix my signature, this seventh day of December, 1918.

DAVID O. ROYSTER.
